UNITED STATES PATENT OFFICE.

JOSEPH THOMAS, OF HOBOKEN, NEW JERSEY.

QUILTING-MACHINE.

SPECIFICATION forming part of Letters Patent No. 289,579, dated December 4, 1883.

Application filed February 10, 1883. (No model.)

To all whom it may concern:

Be it known that I, JOSEPH THOMAS, of Hoboken, county of Hudson, State of New Jersey, have invented certain new and useful 5 Improvements in Sewing-Machines for Quilting, of which the following is a specification.

This invention relates to that class of sewing-machines such as is shown in the United States Letters Patent No. 257,786, granted to 10 me May 9, 1882, which is designed to produce various quilting-patterns, and in which a row of needles moves laterally over the goods, and the feed-rollers are constructed to be adjusted at different angles to the needles.

15 In the present invention two stationary rows of needles are employed, and the stitches made to produce the various patterns by giving to the feed-rollers and all other parts that control the piece of goods to be quilted a longitudinal movement—that is, a lateral movement to the goods at the same time the feed-rollers are moved to feed the goods forward. This I accomplish by means of simple and effective mechanism adapted to be adjusted and 20 changed, so that the relation of the forward feed to the lateral movement of the goods is such as to produce stitches of substantially 25 equal lengths to produce the design desired.

Figure 1, Sheet 1, of the accompanying drawings, represents a front elevation of my improved sewing-machine for quilting. Fig. 2, Sheet 1, is a plan view of the same with the needle-carrying mechanism removed. Fig. 3, Sheet 2, is a transverse sectional view cut on 35 the line $y-y$, looking toward the left hand. Fig. 4, Sheet 2, is a similar view cut on the line $x-x$; and Fig. 5, Sheet 2, is an end elevation, looking toward the right hand. Fig. 6, Sheet 3, is an enlarged detached elevation of the 40 variable feed operating devices; and Fig. 7, Sheet 3, is a section of the same through the line $z-z$, looking toward the right hand.

a represents the main bed of the machine; b , standards secured thereto, which carry the 45 needle-bar c and shuttle-carriers d d' . Two rows of needles, c' and c'' , are used, secured to one needle-bar c , which is operated through the medium of the connecting-rods c^3 c^3 and rocker-shaft c^4 from the main driving-shaft e 50 in the ordinary manner and by the usual connecting devices, as are the two sets of

shuttle-carriers d d' . Said connecting devices are not shown in the drawings, such forming no part of my present invention.

It will be observed that the needles have 55 imparted to them only a vertical reciprocating movement to cause them to pierce the goods, which are given a compound movement under the needles to produce the design desired by means of the devices as follows: The 60 shaft f of the feed-roller f' and the shaft of the presser-roller g are fitted to slide longitudinally, as well as to rotate in open bearings in the standards b b , to facilitate placing the goods between them. These rollers f and 65 g are connected together by means of plates g' g'' , so that the roller g is caused to move longitudinally with the roller f' . Fitted between fixed collars on the shaft f are two arms, h h , the front ends of which rest upon the curved 70 guide-plate h' , as at h^2 , Fig. 3. In these arms h h is fitted to rotate the roller i , around which passes the endless apron i' , carried at its other end by the small roller i'' , also fitted to rotate in the arms h h . The roll of goods j to be quilted 75 rests on the endless apron on the roller i , being held in slots formed in the ends of the arms h h . The object of the endless apron is to facilitate the forward movement of the goods as they leave the roll j to pass under 80 the needles c' c'' to the feed-roller f' . By this arrangement of imparting directly to the feed-roller a transverse movement, instead of moving the needles and their attending operating devices transversely over the goods, or moving 85 a heavy frame carrying the feed-roller, goods, &c., a much less weight has to be moved. Consequently I am enabled to run this class of sewing-machines at a greater rate of speed 90 than heretofore, and the machines are made thereby more durable.

To impart the compound movement to the feed-roller f' and its attending devices to control the goods, a gear-wheel, l , is secured to its shaft f , which meshes into the long idle-pinion l' , driven by the gear-wheel l'' on the shaft m , fitted to rotate in bearings m' m'' , secured to the bed-plate a . On the inner end of the shaft m is secured the cam n , actuating the lever n' by means of a roller thereon. The 95 lower end of this lever is pivoted to a bracket on the under side of the bed at n^2 , and the up-

per end of the lever is forked and fits into a grooved collar, n^3 , on the shaft f , thereby causing the roller f' to move longitudinally in its bearings when the cam n is rotated, the gear-wheel l remaining in gear with the pinion l' , so that the roller may be rotated at the same time it slides in its bearings, the relative extents of such movements being governed by the configuration of the cam n and the amount of rotation given to the shaft m for each stitch made by the needles. This variable intermittent rotation of the shaft m is produced by means of a ratchet-wheel, o , having teeth of different lengths, and actuated by a pawl, p , carried by the lever p' , pivoted on the shaft m and actuated by the eccentric q on the driving-shaft e . The throw of this eccentric is sufficient to move the pawl p over a distance equal to the longest tooth in the ratchet-wheel o .

20. To enable the pawl p to properly catch in the various teeth in the ratchet-wheel o , a variable stop for the lever p' is provided, which consists of the lever r , pivoted to the bracket r' , and having a projection, r^2 , adapted to bear 25 on the cam s , and on the free end of the lever r is secured an adjustable arm, r^3 , bent round at its lower end to hold up the lever p' when it is dropped by the eccentric q . The rises of the cam are so proportioned and bear such relation to the ratchet-wheel o that each time the ratchet is fed forward a tooth by the pawl p the stop r^3 retains the lever in the proper position for the pawl p to catch in the succeeding tooth of the ratchet, when the lever p' is 30 again raised by the eccentric q .

In the drawings, Figs. 6 and 7 show the lever p' and pawl p held by the adjustable arm r^3 of the lever r in position for the action of the eccentric q . The pawl p is about to make its 35 shortest stroke. In Figs. 1 to 5, inclusive, these devices are shown at the end of this stroke of the pawl p . The arm r^3 is in these views in position for the next and longest stroke of the pawl p .

40. t is a spring for holding the projection r^2 of the lever r against the cam s .

The teeth in the ratchet-wheel o may be made uniform in size, and the cam s made so as to cause the pawl p to move the wheel any desired

and variable number of teeth to impart the 50 right motion to the goods to produce the pattern desired. The ratchet o and cams n and s may be readily changed and replaced by others to impart to the goods the right proportional amounts of longitudinal and transverse 55 movements for any pattern of stitches which may be produced by means of two rows of needles. The form of cam and ratchet shown produce the design as illustrated by dotted lines in the plan view, Fig. 2.

60 In forming a simple diagonal or diamond pattern, the cam s and its attending stop-lever r may be dispensed with, the teeth of the ratchet o and form of the cam n being such as to impart a uniformly compound movement to 65 the goods.

What I claim, and desire to secure by Letters Patent, is—

1. The combination of the shaft f , carrying the feed-roller f' , constructed and operated by means substantially as described, with the arms h , rollers i and i^2 , apron i' , and presser-roller g , as and for the purpose set forth.

2. In combination, the feed-roller f' , gear-wheel l , long pinion l' , gear-wheel l^2 on the shaft m , actuated by means substantially as described, and cam n , also on the shaft m , and forked lever n' , as and for the purpose set forth.

3. As a variable device for feed-rollers of 80 quilting sewing-machines, the variable toothed ratchet-wheel o and its operating-pawl p and lever p' , in combination with the stop-lever r , automatically controlled by the cam s , substantially as and for the purpose set forth.

4. In combination, the feed-roller f' , gear-wheel l , long pinion l' , gear-wheel l^2 on the shaft m , cam n , also on the shaft m , forked lever n' , ratchet-wheel o , lever p' , provided with the pawl p , eccentric q , cam s , and stop-lever r , substantially as set forth.

In testimony whereof I have hereunto set my hand, at New York, county and State of New York, this 7th day of February, 1883.

JOSEPH THOMAS.
